INCINERATION

George R. Lewers, Brooklyn, N. Y., assignor, by
mesne assignments, to Underpinning & Foun-
dation Company, Inc., New York, N. Y., a cor-
poration of New York

Application December 4, 1936, Serial No. 114,124

9 Claims. (Cl. 110—12)

This invention relates to incineration and more particularly to improvements in tiered multiple-hearth furnaces and to improvements in processes for drying and burning material by passing it downwardly through a plurality of zones, gradually drying it in upper zones and then burning it in lower zones.

Although the apparatus and process of the present invention are suitable for use with many kinds of material, they are of particular value in drying and burning waste material such as garbage and sewage material including sewage sludge and sewage screenings both of which have a substantial moisture content.

The principal objects of the invention are to provide novel and advantageous forms of apparatus and processes for treatment of material of the general character specified. Another object relates to the condensation and removal of vapors from the gases passing from the drying zones to the burning zones where the material under treatment is passed downwardly through a plurality of drying zones and then through a plurality of burning zones. A further object relates to improvements in the heating within a multiple-hearth furnace of air supplied to the furnace.

The invention may be carried out in connection with a multiple-hearth furnace divided into an upper drying section and a lower burning section by an intermediate hearth having a gas seal through which the solids are fed in correspondence with the downward discharge through the other hearths due, for example, to the action of rabbling devices supported and operated by a hollow vertical shaft. A current of heated air may be passed through the drying zones in contact with the material on the various hearths and then laden with vapors of moisture and volatile substances may be discharged therefrom. Ordinarily the air thus laden with vapors would be passed, either with or without reheating, into the burning section of the furnace. According to the present invention, however, vapors mixed with the air are condensed and removed before the air is introduced into the burning section.

The air to be introduced into the drying section of the furnace may be supplied through a hollow vertical shaft used in operating rabbling devices whereby the solid material on the various hearths is agitated and fed to the outlets thereof for passage downwardly through the furnace. Heretofore air supplied to the lower end of a shaft of this kind has been conducted directly through the hollow shaft to a desired point and then discharged through an outlet or nozzle into

a compartment of the furnace. The shaft serves as a heat exchanger and the air passing therethrough is heated to some extent before being discharged into the furnace. The present invention contemplates a greater heating of the air before it is discharged into the furnace. In carrying out this feature of the invention, direct flow of air through the hollow shaft may be shut off by a suitable obstruction and the air may be by-passed around the obstruction through a suitable heat exchanger carried by the shaft. The heat exchanger may consist of an inlet chamber or duct surrounding the shaft and communicating with the interior of the shaft below the obstruction, a discharge chamber or duct surrounding the shaft and communicating with the interior of the shaft above the obstruction, and a plurality of ducts or tubes parallel to the shaft and connecting the inlet and discharge chambers.

Other objects, features and advantages will appear upon consideration of the following detailed description and of the drawing in which the figure is a view in vertical section of apparatus embodying a preferred form of the invention.

Referring to the drawing, the invention may be embodied in a furnace 10 provided with a top 11 and hearths 12, 13, 14, 15, 16 and 17, of which the hearth 17 serves as a bottom of the furnace or furnace chamber.

The material to be treated may be introduced into the furnace and deposited upon the uppermost hearth 12 through a hopper 18 and a chute 19 extending through the top 11 of the furnace and provided with a pivoted door or gate 20 normally held closed by suitable means such as a weighted arm 21. As soon as a sufficient amount of material to overcome the action of the weighted arm 21 collects on the door or gate 20, the door swings downwardly about its pivotal support and permits the material on the door to fall to the hearth 12.

As illustrated, this material falls on the hearth 12 near its periphery and is worked inwardly to a central discharge opening 22 by suitable rabbling means including one or more radial arms 23 and inclined blades 24 carried thereby. Below the hearth 12, the hearths 13 and 15 are provided with peripheral outlets 25, the hearths 14 and 16 are provided with central outlets 22 corresponding with the central outlet of the hearth 12, and the lower hearth 17 is provided with a single outlet or chute 26 through which the ash is discharged from the furnace. The chute 26 is preferably provided with a gas seal in the form

of a pivoted door 27 normally held in closed position by a weighted arm 28.

The material on the hearths 13, 14, 15, 16 and 17 is moved towards the corresponding outlets by 5 suitable rabbling means similar to that used above the hearth 12, the blades 28 above the hearths 13, 15 and 17 being so inclined as to carry the material outwardly to the peripheral outlets thereof, and the blades above the hearths 14 and 10 16 being so inclined as to work the material toward the central opening as in the case of hearth 12.

The rabbling arms 23 may be supported and 15 operated by a hollow vertical shaft 29 passing through the central parts of the central outlets 22 of the hearths 12, 14 and 16 and through small 20 openings in the top 11 and the hearths 13, 15 and 17, suitable gas seals being provided where the shaft 29 passes through the top and these 25 hearths. The shaft 29 may be rotated in any 30 suitable manner as by means of a bevel gear 30 thereon, a bevel gear 31 meshing with the bevel gear 30, and a pulley 32 connected with the bevel gear 31 and driven from any suitable source of 35 power.

The furnace may be divided into an upper or 40 drying section and a lower burning section by the hearth 13 which preferably has but one outlet 45 provided with a valve or gas seal through which the solid material may be fed while an effective gas seal is maintained. Although this 50 valve may take different forms, that disclosed comprises a tube 33 in said outlet 25, a conical 55 valve or valve member 34 adapted to cooperate with the lower end of the tube 33 and urged to closing position by suitable means which may 60 comprise a lever 35 pivoted at 36 and having a pivotal connection with the valve member 34. The lever 35 passes through the side of the tube 65 33 and through the wall of the furnace, the outer arm being urged downwardly by a weight 37. Division of the furnace in this way renders possible better control of the flow of air and gases 70 through the various parts of the furnace.

Air may be supplied to the drying section 75 through the hollow shaft 29, to the lower part of which air may be supplied by a fan 38 and connecting duct 39. The air passing up through the furnace in the hollow shaft will be heated by 80 heat exchange with the contents of the burning zones and in this preheated condition may be discharged into the upper part of the drying section through one or more outlets or nozzles 40. Heretofore, the air has been passed through the 85 hollow shaft from an inlet to an outlet.

In the present instance, it is desired to utilize 90 the heat from the burning material in the burning zones to raise the temperature to a higher level. To this end, direct flow of the air through the hollow shaft may be prevented by providing 95 the hollow shaft at a suitable point with an obstruction or dam 41 to shut off the flow and divert the stream through a heat exchanger 42 carried by the shaft. This heat exchanger may be of the duct or pipe type and comprise a lower hollow ring 43 communicating with the interior of the shaft 29 below the dam 41 through one or more 100 connections 44, an upper hollow ring 45 communicating with the interior of the shaft 29 above the dam 41 through one or more connections 46. Hot gases of combustion may engage 105 the ducts of the heat exchanger 42 at all sides and provide effective heat exchange.

The usual compartment over a burning hearth 110 would not ordinarily be high enough to accom-

modate a heat exchanger of desired capacity. It may therefore be convenient to utilize two compartments of the burning section by arranging for the heat exchange to pass through the central outlet of a hearth having this type of outlet. 5 As herein disclosed, the heat exchanger 42 extends through the hearth 14 of which the central outlet is made larger for this purpose. The requirement for space may also be met by spacing certain hearths farther apart, thus providing 10 higher compartments. As shown on the drawing, the compartment above the hearth 15 is of greater height than the other compartments.

The air supplied to the uppermost compartment or zone of the drying section may be passed 15 downwardly through the section, that is concurrently with the flow of the solids, and discharged from the lowermost drying compartment through a duct 41 to a condenser 48. This condenser may comprise a chamber 49 with a drainage sump at 20 its bottom discharging through a drain or drain pipe 50, and a pipe system or coil 51 in the chamber connected at one end with a supply pipe 52 and discharging at the other end into the sump at the bottom of the chamber 49, the condensate 25 and condenser water flowing away together through the drain 50. The liquid discharged through the drain 50 may be carried away with the sewage filtrate resulting from a preliminary 30 dewatering of the sewage sludge, or may be returned to the sewage stream before it reaches the filter. In this connection attention may be called to the high moisture content of the sewage sludge fed to the furnace and the resulting large 35 volume of water vapor flowing out of the drying section with the air stream. Obviously there will be a large amount of liquid condensed in the condenser.

From the condenser, the relatively dry air is 40 passed through a duct 53 to the burning section, 45 preferably into the lowermost compartment thereof.

The air and hot combustion gases flow upwardly through the burning section and are discharged therefrom, preferably from the uppermost compartment, through a duct 54, which 50 may lead through a suction fan to a stack.

Obviously the number of hearths in the drying and burning sections may be varied. For use in starting and whenever needed, the various compartments or zones may be provided with burners 55 and doors 55.

It should be understood that various changes 60 may be made and that certain features may be used without others without departing from the true scope and spirit of the invention.

Having thus described my invention, I claim:

1. In combination with a tiered multiple-hearth furnace divided into a drying section and a burning section by a hearth having a gas seal through which solid material may be fed, means for supplying air to the drying section, and means for discharging hot combustion gases from the burning section, a condenser and means for withdrawing air laden with vapors from the drying section and passing it through said condenser to the burning section.

2. In combination with a tiered multiple-hearth furnace divided into a drying section and a burning section by a hearth having a gas seal through which solid material may be fed, means for supplying air to upper part of the drying section, and means for discharging hot combustion gases from the burning section, a condenser and 70

- means for withdrawing air laden with vapors from the lower part of the drying section and passing it through said condenser to the burning section.
5. 3. In combination with a tiered multiple-hearth furnace divided into a drying section and a burning section by a hearth having a gas seal through which solid material may be fed, means for supplying air to the drying section, and means for discharging hot combustion gases from the upper part of the burning section, a condenser and means for withdrawing air laden with vapors from the drying section and passing it through said condenser to the lower part of the burning section.
10. 4. In combination with a tiered multiple-hearth furnace divided into a drying section and a burning section by a hearth having a gas seal through which solid material may be fed, means for supplying air to the drying section, and means for discharging hot combustion gases from the burning section, a condenser and means for withdrawing air laden with vapors from the drying section and passing it through said condenser to the lower part of the burning section.
15. 5. In combination with a tiered multiple-hearth furnace comprising upper drying compartments and lower burning compartments, and a hollow shaft supplied with air at its lower part and discharging air into a drying compartment, means for blocking the passage of air through a part of said shaft in the burning zones and a heat exchanger surrounding said shaft and by-passing air around the blocking means.
20. 6. In combination with a tiered multiple-hearth furnace comprising upper drying compartments and lower burning compartments, and a hollow shaft supplied with air at its lower part and discharging air into a drying compartment, means for blocking the passage of air through a part of said shaft in the burning zones and a heat exchanger surrounding said shaft and by-passing air around the blocking means, said heat exchanger comprising a duct surrounding said shaft and communicating with its interior below the blocking means, a second duct surrounding said shaft and communicating with its interior above the blocking means and a plurality of ducts connecting the first and second mentioned ducts.
25. 7. In combination with a tiered multiple-hearth furnace comprising upper drying compartments and lower burning compartments, and a hollow shaft supplied with air at its lower part and discharging air into a drying compartment, means for blocking the passage of air through a part of said shaft in the burning zones and a heat exchanger surrounding said shaft and by-passing air around the blocking means, said heat exchanger comprising a duct surrounding said shaft but spaced therefrom and communicating with its interior below the blocking means, a second duct surrounding said shaft but spaced therefrom and communicating with its interior above the blocking means and a plurality of ducts connecting the first and second mentioned ducts.
30. 8. In combination with a tiered multiple-hearth furnace comprising upper drying compartments and lower burning compartments, and a hollow shaft supplied with air at its lower part and discharging air into a drying compartment, means for blocking the passage of air through a part of said shaft in the burning zones and a heat exchanger surrounding said shaft and by-passing air around the blocking means.
35. 9. In combination with a tiered multiple-hearth furnace in which the hearths are provided alternately with central and peripheral outlets for downward passage of the solids under treatment, and a central hollow shaft receiving air at its lower part and discharging it into the furnace above an upper hearth, said shaft passing through the central parts of the central outlets of alternate hearths and with gas-seal connections through the other hearths, a heat exchanger surrounding said shaft and extending through one of said central outlets, and means for passing air supplied through the heat exchanger through the hollow shaft.
40. 10. In combination with a tiered multiple-hearth furnace comprising upper drying compartments and lower burning compartments, and a hollow shaft supplied with air at its lower part and discharging air into a drying compartment, means for blocking the passage of air through a part of said shaft in the burning zones and a multiple duct heat exchanger surrounding said

GEORGE R. LEWERS.
